TOWEL DISPENSING DEVICE

James E. Trehwitt and Charles A. Old, Oakland, Calif., assignors to Joseph N. Borroughs, Oakland, Calif.

Application May 13, 1935, Serial No. 21,096

4 Claims. (Cl. 312—38)

This invention relates generally to devices, such as those found in public wash rooms, for dispensing towels.

It is an important object of the invention to provide a dispenser, of the character described, which will insure that the user is receiving, at each instant of requirement, a fresh and sanitary towel.

Other objects of the invention are: to provide a towel dispenser which may be operated by means other than by hand manipulation; to provide a towel dispenser in which the towels are shielded from contamination during the intervals in which the device is not in use; to provide, in a towel dispenser, means for preventing soiling of the towels by coming into contact with lubricants used in the operating mechanism; to provide, in a towel dispenser of the continuous web type, improved means for intermittently feeding the web; to provide, in a dispensing device for continuous web towels, means for conveniently and expeditiously charging the device with a new supply of toweling; to provide, in a towel dispenser, improved means for preventing retraction of the towel during its passage through the dispenser; and to provide an efficient towel dispenser and one which may not readily be tampered with.

Referring to the drawings:

Figure 1 is a front elevation of a towel dispenser incorporating the improvements of our invention.

Figure 2 is a vertical sectional view taken in the plane indicated by the line 2—2 of Figure 1.

Figure 3 is a front elevation of the device of Figure 1 with the front wall thereof removed.

Figure 4 is an enlarged sectional view of a portion of the device of Figure 3. The plane in which the view is taken is indicated by the line 4—4 of the latter figure.

Figure 5 is a view similar to Figure 4 showing the towel magazine in its open or loading position.

Figure 6 is a vertical sectional view of the dispenser showing the operating mechanism. The plane of section is indicated by the line 6—6 of Figure 3.

Figure 7 is a front elevation, enlarged, of the drive roller mounting.

Figure 8 is a sectional elevation of the mechanism of Figure 7. The plane of section is indicated by the line 8—8 of the latter figure.

Figure 9 is an end elevation of the drive roller ratchet mechanism.

In detail, and as will best be seen in Figures 3

to 6 inclusive, the mechanism of my invention is adapted to be housed within a cabinet comprising side walls 5 and 6 which are joined, along their longitudinal edges, with a back wall 7. A top 8 and a bottom 9 are provided joining all 5 of the three wall members at their respective ends, and a front wall member 11 is provided being movably secured to the side wall 6 by means of a plurality of hinges 12 and having mounted thereon a lock 13 the bolt of which is adapted 10 to engage a socket 14 formed adjacent the edge of the side wall 5 remote from the back wall 7. The front wall member thus really forms a door which may be opened to permit access to the interior of the cabinet. A central portion of the 15 door is removed to provide a dispensing aperture 16, and a shutter 17 is disposed immediately behind the aperture and is mounted for movement thereacross by means of a pair of guide rails 18 which are adapted to receive a plurality 20 of clips 19 fastened to the vertical edges of the shutter. It will thus be seen that the shutter may be moved vertically, in the guide rails, to a position where the dispensing aperture is uncovered, or lowered to the position illustrated 25 wherein the aperture is closed.

Means are provided for mounting a continuous web of toweling adjacent the dispensing aperture. As will best be seen in Figure 2 a magazine is disposed in the upper section of 30 the cabinet and comprises a bottom plate 21 having a vertical baffle plate 22 secured to its forward edge just back of the door 11; the edges of both the baffle plate and the bottom plate being secured to a pair of spaced side plates 23 and 24, 35 portions of each of which are extended downwardly beyond the bottom plate 21 to provide a pair of spaced parallel brackets 26 and 27.

Positioned substantially centrally of the brackets are a pair of rotatable rubber covered feed 40 rollers 28 and 29, the former of which is fixedly journaled in the brackets and the latter being mounted for movement radially to and from the fixed roller. This construction is clearly illustrated in Figures 4 and 8 in which each bracket 45 is shown as being provided with a slot 31 in which is slidably mounted a journal block 32, one of these being provided for each end of the movable roller. Resilient means such as a tension spring 33, having one end secured to the journal block and the other end thereof secured to the bracket, are provided for resiliently urging the rollers into peripheral engagement. A set of feed rollers 34 and 36, similar to those just described, are mounted between the side plates 50 55

23 and 24 of the magazine in a position so that they lie closely adjacent the upper edge of the baffle plate 22. The roller 36 of this latter group is, of course, spring pressed into engagement 5 with the fixed roller 34 in the same manner as was described in connection with the roller 29.

Disposed in the magazine, and resting on the bottom plate 21 thereof, is a roll 37 of toweling, the web 38 of which is led upwardly between the 10 rollers 34 and 36, thence downwardly in a deep loop 39 terminating adjacent the lower edge of the door 11, thence upwardly to where it passes between the feed rollers 28 and 29 and thence downwardly where it falls in folds in the waste 15 compartment 41 in the bottom of the cabinet. In order to preserve the loop 39 a heavy roller 42 is provided therein which is rotatably mounted on brackets 43 suitably guided in grooves 44 formed in each side wall of the cabinet.

20 It will be seen from the above that, when the shutter 17 is raised exposing the dispensing aperture 16, the web 38 will be within easy reach of the user. To preclude the possibility of the user grasping both webs of the loop 39, a separator 25 plate 46 is disposed between the two webs immediately back of the dispensing aperture. The plate 46 is pivotally mounted on the brackets 26 and 27 by means of pivot pins 47 so that the plate may be swung outwardly to a position where it 30 will not interfere with the operation of threading a new web of toweling into the machine when the latter requires recharging.

Means are provided, associated with the feed rolls 28 and 34 for preventing the web from 35 circling the rolls and disabling the mechanism. It will be noted that the surfaces of each of the rolls mentioned above is cut away to provide a plurality of spaced grooves 48 in which are mounted, for free movement therein, a series of 40 looped bars 49 extending downwardly from the rollers. The lower end of each bar terminates in an eye 51 in which is secured a tie bar 52 which serves to secure all of the looped bars together. As will be seen, by reference to the rollers 28 and 45 29 of Figure 2, the bars 49 prevent that portion of the web 38 leaving the periphery of the roller 28 to enter the waste compartment, from continuing around the roller and becoming caught between the periphery thereof and that portion of 50 the web approaching the roller. This might happen, in the absence of the guard bars 49, if there chanced to be a sticky substance on the surface of the soiled web contacting the periphery of the roller 28. The adhesion of the web 55 to the roller caused by this substance would cause the web to continue encircling the roller with the result that the feeding mechanism would become jammed and disabled.

Means are provided for operatively connecting 60 together the two sets of feed rollers so that the amount of soiled web fed into the waste compartment, by the feed rollers provided for this purpose, will be replaced by an equal amount of fresh web fed from the magazine by the other set 65 of feed rollers. Referring to Figures 3 and 4 of the drawings, it will be seen that the shaft of the feed roller 34 is extended beyond the side plate 24 and is provided with a sprocket 53 which carries a chain 54 directed downwardly and engaged 70 with a similar sprocket 56 formed integrally with a spur gear 57. Both the gear 57 and the sprocket 56 are freely journaled on a stub shaft 58 which is mounted in the side plate 24; the outer end of the stub shaft being supported by an outboard 75 bearing 59. The end of the shaft of the roller

28 is provided with a spur gear 61 which meshes with the gear 57 and an outboard bearing 62 is provided for supporting the end of the roller shaft. It will be seen therefore that both sets of rollers are positively connected by means of the gears, and by the sprockets and chain, for rotation together, the rotation of the roller 28, of course, being reversed in direction to that of the roller 34. Referring back to Figure 2 again, it will be seen that the amount of fresh web fed 10 from the magazine by the feed rollers 34 and 36 will be equaled by the amount of soiled web fed into the waste compartment by the feed rollers 23 and 29 due to their operative interconnection.

Means are provided for simultaneously, intermittently feeding a fresh portion of the web past the dispensing aperture, feeding an equal amount of soiled web into the waste compartment, and opening the shutter to expose the fresh web whereupon it may be grasped and drawn through the dispensing aperture by the user. All of these operations are performed by a single motion of the user and do not require the use of his hands.

The mechanism for performing these functions 25 is shown, practically in its entirety in Figure 6, and comprises a foot treadle 63 which extends through a slot 64 formed in the front wall of the cabinet and is pivotally mounted on a bracket 66 which is secured to the base 9. A lever 67 is 30 pivotally mounted on a bracket 68 secured to the side wall 6 of the cabinet approximately midway of its height and a link 69 is provided for joining the lever and the treadle together. Both the lever and the treadle are each provided with 35 a row of spaced apertures 71 by means of which the fulcrum points of the link pivots 72 may be adjusted so as to vary the degree of relative movement between the treadle and the lever. The outer end of the lever 67 is provided with an 40 eye 73 which engages a cord 74, provided at one end with a counterweight 76, and extending upwardly and over a sheave 77 secured to the side wall of the cabinet adjacent the top thereof. After leaving the sheave 77 the cord passes over 45 another sheave 78 located adjacent the pivotal axis of the door 11 and thence passes across the interior surface of the door, over a third sheave 79, and downwardly to be secured by means of a clip 81 to the shutter 17. From the description 50 so far it will be seen that foot pressure to depress the treadle 63 will cause the lever 67, due to its interconnection with the treadle through the link 69, to swing downwardly thereby causing movement of the cord 74 through the sheaves 55 55 78 to open the shutter 17. Since it is desirable to keep the cord 74 taut at all times, the cord is not fixedly secured to the lever 67 but, as was mentioned above, passes through the eye 73 thereof and a collar 82 is secured to the cord 60 slightly below the eye so that the lever is required to swing a short distance downwardly before it picks up connection with the cord. The function of the weight 76 therefore is to both counter-balance the weight of the shutter and to maintain 65 a desired tension in the cord.

Means are provided for connecting the lever 67 and the feed roller drive mechanism. As is shown in Figures 3 and 9, the shaft 83 of the feed roller 28, at the end thereof opposite to that to 70 which the feed roller inter-connecting gearing described above is mounted, is provided with a ratchet 84 secured for rotation therewith. A sprocket 86 is journaled on the shaft 83 and has secured thereto a disk 87 which carries a pawl 88 75

adapted to engage the teeth of the ratchet 84. A resilient arm 89 is secured to the disk 87 and is provided with an end portion which passes through a slot 91 formed in the disk and bears against the pawl to resiliently urge the latter into engagement with the ratchet teeth.

Referring again to Figure 6 it will be seen that the sprocket 86 is positioned slightly above the lever 67 and a chain 92 is secured at one end thereof to the lever 67, passes over the sprocket 86, and extends downwardly to be connected through a long coiled spring 93 with a pin 94 secured to the side of the cabinet. Since the sprocket 86 is connected with the shaft 83 through the ratchet and pawl mechanism the feed rollers will only be rotated during the downward movement of the treadle; the entire mechanism returning to normal position during the up-stroke of the treadle under the contraction of the spring 93, without affecting the rollers since the connection therebetween is uni-directional.

Means are provided for resiliently resisting the sudden return of the mechanism to normal position when the pressure is released from the treadle. Mounted on the side wall of the cabinet below the lever 67 is a pneumatic cylinder 96 having a movable piston therein connected with a piston rod 97 which is secured, by means of a link 98 with the lever 67. The end of the cylinder 96 is provided with a nipple 99 having an aperture therethrough which communicates with the interior of the cylinder for admitting air thereto, and a screw 101 is provided projecting into the aperture so that the cross sectional area thereof may be varied and consequently the volume of air capable of passing through the aperture in a given time may be also varied. By means of the air cylinder therefore the speed at which the parts of the mechanism may assume their normal positions may be adjusted as desired, partly to avoid subjecting the mechanism to severe shocks and partly to prevent the shutter 17 closing too rapidly and perhaps striking and injuring the user's hand.

Means are provided for preventing a reversal of movement of the web through the feed rollers to preclude the possibility of a soiled portion of the web being left in alignment with the dispensing aperture to be unknowingly used by a succeeding person. As shown in Figures 7 and 8 the shaft 102 of the feed roller 34 is provided with a disk 103 having a peripheral flange 104 thereon which is provided with a notch 106. A latch dog 107 is pivoted on the disk, by means of a pin 108, and projects through the notch 106, the end of the latch dog being positioned a short distance beyond the surface of the flange 104. The disk 103, being mounted on the feed roller 34, will rotate therewith when the roller is turned and will carry around with it the latch dog. When the dog is in the position shown in the figure, the end thereof will lie in abutting relationship with the side member of the bracket, and due to this relationship the shaft 102 is prevented from rotating in a clockwise direction. Thus the web 38 is prevented from moving in but one direction that being from the upper magazine to the waste compartment.

Means are provided for permitting the magazine to be tilted forward so as to permit the loading of a fresh roll of toweling thereto. As will be seen in Figures 4 and 5, each of the lower right hand corners of the magazine is provided with a stud 109 which is journaled in a clip 111 fixed to the side wall of the cabinet. As shown in

Figure 5 this permits the magazine to be tilted forward so that the open upper end thereof is exposed thereby allowing a new roll of toweling to be readily placed therein. To limit the forward movement of the magazine an angle bar 112 is secured thereto which projects at each end beyond the side walls of the magazine, and, when the latter is in its forward position, abuts against a bracket 113 secured to the side wall of the cabinet, and, when the magazine is in its upright position, rests on a pair of clips 114 secured to the side wall of the cabinet adjacent the back wall thereof. It will be observed that the connection between the chain 92 and the sprocket 86 will not be affected when the magazine is moved due to the spring connection of the chain with the cabinet and the fact that the sprocket will roll along the chain when its position is changed with respect to that shown in Figure 6.

Means are provided for shielding the web of toweling from the operating mechanism of the device so as to prevent soiling of the web by lubricants used on the mechanism. As is best shown in Figures 2 and 3, a door 116 is provided for the waste compartment being hinged to the side wall of the cabinet and disposed to lie immediately back of the loop 39, and this door cooperates with a side partition 117 and a bulkhead 118 to completely isolate the waste compartment from the various levers, rods, etc., making up the operating mechanism, this mechanism, as will be seen in Figure 3, being disposed in the space between the partition 117 and the side wall of the cabinet.

In operation, after a roll of toweling 37 has been placed in the magazine and the web 38 thereof threaded through the feed rollers, pressure of the operator's foot on the treadle 63 will cause the latter to swing downwardly thereby causing a downward movement of the lever 67. This will cause the chain 92 to be drawn over the sprocket 86 causing rotation of the latter and, due to the operative relationship of this sprocket with the feed rollers, will cause the latter to rotate and feed a quantity of the web past the dispensing aperture 16. Simultaneously with the operation of the feed rollers the cord 74 will be tensioned thereby raising the shutter 17 and exposing the web 38 whereupon it may be grasped by the user. It may be then drawn through the dispensing aperture over the guide roller 119, which is provided to decrease the friction of the web with the lower edge of the dispensing aperture, and utilized. The act of drawing the loop of toweling through the aperture will, of course, shorten the loop 39 the roller 42 thereof rising as the quantity of toweling drawn through the aperture increases. When the user has finished with the towel he releases the web which immediately springs back into the aperture, under the pressure of the descending roller 42, whereupon release of the pressure from the treadle will allow the shutter to close and the operating mechanism to return to its normal position whereupon it is ready to repeat the cycle of operations when the treadle is again depressed.

Having thus described our invention it will be seen that we have provided a towel dispenser which is capable of shielding the toweling from contamination during intervals when the mechanism is not in use, one which insures that there is always a clean towel ready for the user, one which permits movement of the web of toweling in but one direction, and one in which the mech-

anism for feeding the web is considerably improved.

We claim:

1. In a dispensing device for continuous web toweling comprising a cabinet having a dispensing aperture therein, a closure for said aperture, a magazine adapted to hold a roll of said toweling, and a waste compartment in said cabinet, means for feeding pre-determined portions of said toweling from said magazine into said waste compartment past said aperture comprising pairs of feed rollers for engaging said toweling in said magazine and said waste compartment, means for connecting said rollers for rotation together, a lever pivotally mounted in said cabinet and having a treadle portion thereof extending exterior of the cabinet, an intermediate lever mounted for pivotal movement in said cabinet in spaced relationship with said treadle lever, a link pivotally connecting said levers, means for adjusting the pivot point of said link on each of said levers to vary the radius of movement of said pivots, an eye at the end of said intermediate lever, a cord having a counterweight at one end thereof, passing freely through said eye and having the other end thereof secured to said dispensing aperture closure, a stop on said cord for limiting the movement of the lever with respect to the cord, a sprocket secured for uni-directional rotation with one of said feed rollers, a chain having one end thereof secured to said intermediate lever and passing over said sprocket, and resilient means connecting the free end of said chain with said cabinet.
2. In a dispensing device for continuous web toweling comprising a cabinet having a dispensing aperture therein, a closure for said aperture slidably mounted in said cabinet, a magazine adapted to hold a roll of said toweling pivotally mounted in said cabinet and movable from a position therewithin to a position exterior thereof, said cabinet having a waste compartment therein for receiving said toweling as it is used, means for feeding pre-determined portions of said toweling from said magazine into said waste compartment past said dispensing aperture comprising pairs of feed rollers for engaging said toweling in said magazine and said waste compartment, said toweling depending from said feed rollers in a loop adjacent said dispensing aperture, means operatively connecting said feed rollers for synchronous rotation together, a lever pivotally mounted in said cabinet and having a treadle portion thereof extending exterior of said cabinet, means operatively connecting said lever with said feed rollers whereby upon depression of said treadle said rollers will be rotated to feed said toweling, and said aperture closure will be moved to uncover said dispensing aperture, said connecting means being adjustable to vary the ratio of movement between said feed rollers and said lever whereby the quantity of toweling fed past said dispensing aperture may be varied, means for yieldingly resisting movement of said lever in both directions of movement thereof, and a plate of material secured to said cabinet and overlying said dispensing aperture between the webs of the toweling of said loop for preventing both webs of said loop to be drawn by the user through the dispensing aperture.
3. In a dispensing device for continuous web toweling comprising a cabinet having a dispensing aperture therein, a closure for said aperture, a magazine adapted to hold a roll of said toweling, and a waste compartment in said cabinet, means for feeding pre-determined portions of said toweling from said magazine into said waste compartment in looped formation past said aperture comprising pairs of feed rollers for engaging said toweling in said magazine and said waste compartment, means for connecting said rollers for rotation together, a lever pivotally mounted in said cabinet and having a treadle portion thereof extending exterior of the cabinet, means operatively connecting said lever with said feed rollers and said aperture closure whereby said rollers will be rotated upon movement of said lever and said aperture closure will be moved to uncover said aperture, said means comprising a sprocket rotatably connected with one of said rollers, a chain engaging said sprocket and operatively connected with said lever, a flexible cord operable by said lever, and connected with said aperture closure, and a rigid member disposed in the loop of said toweling, said rigid member overlying and substantially covering said dispensing aperture.
4. In a dispensing device for continuous web toweling comprising a cabinet having a dispensing aperture therein, a closure for said aperture, a magazine adapted to hold a roll of said toweling, and a waste compartment in said cabinet, means for feeding pre-determined portions of said toweling from said magazine into said waste compartment in looped formation past said aperture comprising pairs of feed rollers for engaging said toweling in said magazine and said waste compartment, means for connecting said rollers for rotation together, a lever pivotally mounted in said cabinet and having a treadle portion thereof extending exterior of the cabinet, a cord operatively connected with said lever and said aperture closure whereby said closure will be moved to uncover the aperture when said lever is moved, means operatively connecting said feed rollers, for uni-directional rotation, with said lever when the latter is moved, and a rigid member overlying and substantially covering said dispensing aperture, said member being spaced from the portion of said cabinet containing the dispensing aperture to provide, between opposite ends of said member and the cabinet, slots through which but one portion of the loop of said toweling may move past said dispensing aperture.

JAMES E. TREWHITT.
CHARLES A. OLD.
